UNITED STATES PATENT OFFICE.

CHARLES A. BACKSTROM, OF CRAFTON, PENNSYLVANIA; MARTHA A. BACKSTROM, ADMINISTRATRIX OF SAID CHARLES A. BACKSTROM, DECEASED, ASSIGNOR TO PITTSBURG WATER HEATER COMPANY, OF PITTSBURGH, PENNSYLVANIA, A CORPORATION OF NEW JERSEY.

BURNER.

1,262,431.

Specification of Letters Patent.

Patented Apr. 9, 1918.

Application filed May 12, 1917. Serial No. 168,100.

To all whom it may concern:

Be it known that I, CHARLES A. BACKSTROM, a citizen of the United States, residing at Crafton, in the county of Allegheny and State of Pennsylvania, have invented 5 certain new and useful Improvements in Burners, of which the following is a specification.

The invention relates to burners and has 10 its greatest utility in connection with water heating, wherein the gas is turned on and off intermittently by a thermostat or water valve, although the burner embodying the invention is not limited to use in such relations. It has for its primary objects; the provision of a burner in which there will be 15 no continued burning at the gas admission tip after the main gas valve has been closed, and which is simpler and cheaper than 20 those heretofore constructed; the provision of a burner in which the necessity for using the customary gauze or foraminous plate or slotted grid is avoided; and the provision of a burner having no parts requiring 25 placement or repair such as is the case with a gauze burner. One embodiment of the invention is illustrated in the accompanying drawings, wherein—

Figure 1 is a partial face view and partial 30 longitudinal section through a burner embodying the invention; Fig. 2 is a vertical section through the burner removed from the spud on the line II—II of Fig. 1; and Fig. 3 is a bottom view of the construction 35 shown in Fig. 1.

In burners as employed in heaters in 40 which the gas is automatically turned on and off, such as water heaters using thermostat and water valve control, it has been the practice to employ a gauze or its equivalent, such as a slotted or perforated plate 45 in order to prevent back firing. This is necessary since, with a gradual turning off of the gas, such as is incident to thermostatic control, the tendency of the flame is to work 50 back into the burner and burn inside the mixing tube. This will also occur, even where a gauze or its equivalent is used, if such gauze becomes broken or cracked, thus giving a larger passageway for the flame to work back. This back firing is disastrous to the proper operation of the burner since

soot is formed inside of the burner by the imperfect combustion. Furthermore, the burner ring upon which the burners are 55 mounted with its supply passage contains a considerable amount of gas after the main gas valve of the heater is closed, so that in case of back firing, the burning at the ends of the burner spuds continues for a 60 considerable time after the gas has been turned off, and may continue until the gas is turned on again, in which case a very extensive combustion occurs inside the burners. This combustion is of course very 65 wasteful, since there is no proper mixture of air and gas, and the burner soon becomes choked by the soot produced. It is the purpose of my invention to provide a simple 70 means which will always prevent back firing and which will avoid the necessity of using a gauze or foraminous plate, since the gauze or foraminous plate is a very considerable item of expense, requiring cleaning and replacement from time to time, and 75 in some cases becoming cracked or broken and permitting the back fire heretofore referred to. The means whereby this object is accomplished will be readily apparent by 80 reference to the drawings.

In the drawings, 1 is the burner or mixer tube and 2 is the burner head, such parts being preferably made in one integral casting and the head being provided with outlet spouts 3, 4 and 5. The construction of this 85 part of the burner is of small moment in so far as the primary invention is concerned, but is important to note that the invention, doing away with the requirement for a gauze or equivalent guard plate, permits of 90 the use of a very simple unitary casting, such as that illustrated, instead of the multi-part burner constructions heretofore required and incident to the use of gauze and other equivalent guard plates.

The lower end of the mixing tube 1 carries the integral collar 6 for fitting over the admission spud, and surrounding this collar 6 are the usual air admission spaces 7. The admission spud 8 is screw-threaded at its 100 lower end for attachment to a burner ring or other supply connection and has an enlarged passage 9 intermediate its ends, the upper end of such passage being closed by

a screw tip 10 having the reduced outlet opening 11. A seat 12 is provided at the lower end of the passage 9 and such seat carries the gravity closing ball check valve 13, preferably made of aluminum or other relatively light material so that it will close lightly and offer only a relatively slight resistance to the upward flow of gas.

By the use of this construction, anything but a momentary burning inside the mixing tube is avoided in case the flames should work back through the burner head as the gas is gradually turned off. The instant the gas pressure is entirely shut off by the gas valve the ball 13 seats, and if any gas is burning at the upper end of the spud at this time, such burning stops, usually with a slight detonation, since the mixture in the tube 1 becomes thinner and more explosive when the supply of gas is cut off. The force thus produced tends to seat the ball 13 still more firmly. As a result, any continued burning at the upper end of the spud is prevented and the volume of gas in the burner ring and connecting pipes on the outlet side of the main gas valve is kept confined by the various ball check valves on the burners until the gas is turned on again at which time the ignition will occur outside of the burner heads.

It will be seen that the burner head contains no small passages to be clogged up by soot or dust so that any occasion for cleaning the burner is slight. Also that the construction is much cheaper than those employing a gauze or equivalent perforated or slotted plate. The gauze or plate is usually made of copper or brass which is expensive, and as heretofore pointed out, the use of such parts in the burner head always involves more or less complication and additional expense. The burner is further not subject to deterioration incident to the usual gauze or other guard plate which may crack and permit back firing at any time and which must be removed and cleaned or replaced at intervals, under the best of conditions. The burner herein described, therefore, not only has a much lower cost, but

its cost of maintenance is less and there is no possibility of back firing and more or less long continued burning inside the mixing tube as is the case with the old type of burner employing the gauze. Other advantages incident to my construction will be apparent to those skilled in the art.

What I claim is.

1. In combination in a burner, an upright admission spud, a relatively light gravity opening check valve in the spud, and a mixing tube having air admission means removably mounted on the spud.

2. In combination in a burner, an upright admission spud externally threaded at its lower end for mounting in a burner ring, a relatively light gravity opening check valve in the spud, and a mixing tube having air admission means removably mounted on the spud.

3. In combination in a burner, an upright admission spud comprising a hollow body portion provided with a valve seat and an outlet plug seated removably on the upper end of the body portion, a relatively light gravity opening check valve mounted on the seat, and a mixing tube mounted on the spud.

4. In combination in a burner, an upright hollow admission spud having a valve seat therein, an aluminum ball upon said seat, and a mixing tube removably mounted on the spud.

5. In combination in a burner, an upright hollow admission spud having a valve seat therein, an outlet plug removably mounted at the upper end of the spud, an aluminum ball upon said seat, and a mixing tube removably mounted on the spud.

6. In combination in a burner, a mixing tube, a gas admission tube, and a gravity closing ball check valve of aluminum in the gas admission tube.

7. A spud for a bunsen burner screw-threaded at its lower end and having a valve seat, an aluminum check valve on the seat, and a cap removably mounted on the spud.

CHARLES A. BACKSTROM.
